HIGHLIGHTING PICTORIAL REPRESENTATION AND PROCESS OF MAKING SAME

Lawrence D. Menconi, 915 Helen Drive, Melrose Park, Ill., and Harold E. Laser, 1380 Jefferson St., Des Plaines, Ill.

Filed Mar. 24, 1961, Ser. No. 98,033
7 Claims. (Cl. 161—34)

This invention relates generally to the graphic arts, and particularly to a highlighted pictorial representation, and a process of making same.

One of the principal objects of the invention is to provide an artistic highlighting effect in a multi-colored pictorial representation.

Another object is to provide a pictorial representation, preferably printed on a metallic foil sheet and characterized by large areas of substantially the same color with a highlighted effect which varies according to the light impinging upon and reflected from the colored areas.

Yet another object comprehends a process for making an article of manufacture as described in the foregoing paragraphs.

Other objects and important features of the invention will be apparent from a study of the following specification taken with the drawings which together describe and illustrate a preferred embodiment of the invention, and what is now considered to be the best mode of practicing the principles thereof. Other embodiments may be suggested to those having the benefit of the teachings herein, and such other embodiments are intended to be reserved especially as they fall within the scope and spirit of the subjoined claims.

In the drawings:

FIG. 1 is a master pictorial representation which it is desired to reproduce to embody the improvements according to the present invention, and discrete color areas thereof being shaded in accordance with standard symbols;

FIG. 2 is a view similar to FIG. 1, but showing in outlines the discrete color areas seen in FIG. 1;

FIG. 3 is a view of a lined screen adapted to be shaped to correspond to one of the discrete color areas seen in FIGS. 1 and 2;

FIG. 4 shows an overlay made from the screen seen in FIG. 3, said overlay corresponding in outline to a discrete color area seen in FIG. 1, and as seen in outline in FIG. 2;

FIG. 5 is a view similar to FIG. 4, but showing an overlay for another area of a same or different discrete color;

FIG. 6 shows the overlays of FIGS. 4 and 5 placed over their corresponding areas;

FIG. 7 is a reversed photo-engraving of FIG. 6, showing the manner in which the parallel lines of the overlying screens extend in different directions;

FIG. 8 is an exploded sectional view through a foil material particularly adapted to have the pictorial representation either printed or off-set thereon; and

FIG. 9, is a view similar to FIG. 1, but showing how the pictorial representation and the material of FIG. 8 is embossed by the photo-engraving seen in FIG. 7, so as to highlight the discrete color areas thereof.

Referring now to the drawings, FIG. 1 shows a pictorial representation illustrated generally by the reference numeral 10, said representation containing areas of substantially different discrete colors, each such color being represented in accordance with the standard symbols referred to in Rule 84 of the Rules of Practice of the United States Patent Office in Patent Cases.

The pictorial representation 10, seen in FIG. 1, may be printed upon a foil sheet 11 seen in FIG. 8. The foil sheet 11 preferably comprises a foil layer 12, an intermedi-

2

ate layer 13 made of suitable deformable material such as wax or plastic or the like, and a backing strip 14. Pictorial representation 10 may be either directly printed upon the foil 12 or placed thereon by a suitable off-set process. As a general proposition, the colored inks employed in making the color pictorial representation 10 are preferably of a translucent type so that the sheen of the foil is partly seen therethrough.

The pictorial representation 10 seen in FIG. 1 is made from a master which can be reduced to its outlined components, the master being referred to by the reference numeral 15; see FIG. 2. Each of the discrete color areas of the pictorial representation seen in FIG. 1 is outlined as seen in FIG. 2. A "one-way screen" 16 having parallel lines or rulings of from 55 to 150 rulings per inch is made of suitable transparent material, see FIG. 3. The screen 16 is shaped to provide an overlay 17 seen in FIG. 4, which corresponds in outline to an outlined area 18 seen in FIGS. 1 and 2. The overlay 17 is placed in position as seen in FIG. 6 on the outline master 15 seen also with respect to FIG. 2. The screen 16 is also suitably cut to provide an overlay 19 adapted to overlay an area 21 seen in FIG. 2, the overlay 19 being shown in position in FIG. 6.

It will be noted from FIG. 1, that area 21 has a different color from area 18 and from FIG. 6 that the direction of the lines of the screen 16 are different in the two overlays 17 and 19. Each of the areas seen in FIGS. 1 and 2 is overlaid as seen in FIG. 6 with overlays of a corresponding outline like those seen in FIGS. 4 and 5 with the lines of each overlay being parallel to each other but extending in different directions from the lines of the overlays of contiguous discrete color areas.

The master outline seen in FIG. 6, when completely covered with the overlays made from the screen 16 in FIG. 3, is then exposed in a photo-engraving process to provide a photo-engraving plate 22 seen in FIG. 7. Obviously, the plate 22 seen in FIG. 7 is a reverse image of that seen in FIGS. 1 and 2. The photo-engraving 22 is made of a size corresponding to the pictorial representation 10 seen in FIG. 1 which is first printed or offset upon the foil 12. The photo-engraving 22 is then brought into register with the pictorial representation 10 seen in FIG. 1 to provide the resulting highlighted pictorial representation 23 seen in FIG. 9.

With the use of translucent inks, and by reason of the embossing effect of the photo-engraving 22 seen in FIG. 7, there results therefrom a pictorial representation having unusual and striking highlighting effects. It has been found that such pictorial representations are of particular value in the advertising of products or for use in calendars, because of the different reflective qualities of the different areas of the pictorial representation and because of the difference in the direction of the light reflected therefrom.

While the invention has been described in terms of a particular pictorial representation made according to the process, it is not intended that the invention be limited to the particular pictorial representation herein shown, and other representations and the process by which the same are made is intended to be reserved.

We claim:

1. A multi-color pictorial representation characterized by highlighting effects, said pictorial representation including a metallic foil covered sheet having colored areas formed thereon of inks having translucent properties so that the sheen of said metallic foil covered sheet appears therethrough, said metallic foil covered sheet being deformable and being deformed subsequent to the emplacement of said colored areas thereon by striations in said metallic foil covered sheet and in said colored areas, all of the striations in a given colored area extending

along parallel axes, and all of the striations of contiguous colored areas extending in different directions from the striations of a contiguous colored area.

2. A multi-color pictorial representation characterized by highlighting effects, said pictorial representation including a metallic foil sheet having colored areas formed thereon of inks having translucent properties so that the sheen of said metallic foil sheet appears therethrough, said metallic foil sheet being deformable and being deformed subsequent to the emplacement of said colored areas thereon by striations in said metallic foil sheet and in said colored areas, all of the striations in a given colored area extending along parallel axes, and all of the striations of contiguous colored areas extending in different directions from the striations of a contiguous colored area.

3. A multi-color pictorial representation characterized by highlighting effects, said pictorial representation including a metallic foil sheet having discrete colored areas formed thereon of inks having translucent properties so that the sheen of said metallic foil sheet appears therethrough, said metallic foil sheet being deformable and being deformed subsequent to the emplacement of said colored areas thereon by striations in said metallic foil sheet and in said discrete colored areas, all of the striations in a given discrete colored area extending along parallel axes, and all of the striations of contiguous colored areas extending in different directions from the striations of a contiguous colored area.

4. The process of making a multi-color pictorial representation characterized by highlighting effects and having areas of different substantially discrete colors, which comprises making a master having outlined areas corresponding to the aforesaid discrete color areas, cutting a first lined screen along an outline corresponding to one of said outlined areas and placing the same on a corresponding area of said master, cutting similar lined screens along outlines corresponding to the other discrete color areas and placing the same on corresponding areas but making the lines thereof extend in directions different from the screens covering contiguous areas, making an engraving from the master so superimposed with the aforesaid lined screens, reproducing said color areas on a metallic foil, and embossing said foil by said engraving.

5. The process of making a multi-color pictorial representation characterized by highlighting effects and having areas of different substantially discrete colors, which comprise making a master having outlined areas corresponding to the aforesaid discrete color areas, cutting a first lined screen along an outline corresponding to one of said outlined areas and placing the same on a corresponding area of said master, cutting successive similar lined screens each along an outline corresponding to the other areas and placing the same on the said corresponding areas but making the lines thereof extend in directions different from the screens covering contiguous

areas, making an engraving from said master so superimposed with the aforesaid lined screens, reproducing said color areas on a sheet, and embossing said sheet by said engraving.

5. The process of making a multi-color pictorial representation characterized by highlighting effects and having areas of different substantially discrete colors, which comprises making a pictorial representation with the aforesaid discrete color areas, cutting a first lined screen along an outline corresponding to the outline of an area of substantially discrete color on said pictorial representation and placing the same on a corresponding area of said pictorial representation, successively cutting similar lined screens each along an outline corresponding to the other discrete color areas and placing the same on the said corresponding areas but making the lines thereof extend in directions different from the screens covering contiguous areas, making an engraving from the pictorial representation so superimposed with the aforesaid lined screens, reproducing said color areas on a metallic foil, and embossing said foil by said engraving.

6. The process of making a multi-color pictorial representation characterized by highlighting effects and having areas of different substantially discrete colors, which comprises making a pictorial representation with the aforesaid discrete color areas, cutting a first lined screen along an outline corresponding to the outline of an area of discrete color and placing the same on a corresponding area of said pictorial representation, successively cutting similar lined screens along outlines corresponding to the outlines of the other discrete color areas and placing the same on the said corresponding areas but making the lines thereof extend in directions different from the screens covering contiguous areas, making an engraving from the pictorial representations so superimposed with the aforesaid line screens, reproducing said color areas on a sheet, and embossing said sheet by said engraving.
